DESIGN FOR A CLIP.

•60,275.

Specification for Design. Patented Jan. 17, 1922.

Application filed December 8, 1919. Serial No. 343,429. Term of patent 7 years.

To all whom it may concern:

Be it known that I, LEWIS J. STONE, a citizen of the United States, residing at Worcester, in the county of Worcester and State of Massachusetts, have invented a new, original, and ornamental Design for a Clip, of which the following is a specification.

Reference is to be had to the accompanying drawing forming part of this specification, in which—

Fig. 1 is a side view;
Fig. 2 is a top view; and
Fig. 3 is an end view of a clip showing my new design.

I claim:
The ornamental design for a clip, as shown.
